US0D1108816S

(12) United States Design Patent (10) Patent No.: US D1,108,816 S
(45) Date of Patent: * Jan. 13, 2026

(54) SOAP DISPENSING SCRUBBER

(71) Applicant: Techtronic Cordless GP, Anderson, SC (US)

(72) Inventors: Jeremy Fedrigon, Greenville, SC (US); J. Luke Jenkins, Williamston, SC (US); Stephen A. Huggett, Anderson, SC (US); Li Hao Yang, Kwai Chung (CN); Li Zhang, Kwai Chung (CN); You Rui Li, Kwai Chung (CN)

(73) Assignee: TECHTRONIC CORDLESS GP, Anderson, SC (US)

() Term: 15 Years

(21) Appl. No.: 29/915,267

(22) Filed: Oct. 27, 2023

(51) LOC (15) Cl. 04-01

(52) U.S. Cl.

USPC D4/102; D4/114

(58) Field of Classification Search

USPC D4/102, 114, 116, 121, 127, 128, 130, D4/132, 133; D8/70; D32/25, 40

(57) CLAIM

The ornamental design for a soap dispensing scrubber as shown and described.

DESCRIPTION

FIG. 1 is a top perspective view of the soap dispensing scrubber;

FIG. 2 is a bottom perspective view of the soap dispensing scrubber of FIG. 1;

FIG. 3 is a first side view of the soap dispensing scrubber of FIG. 1;

FIG. 4 is a second side view of the soap dispensing scrubber of FIG. 1;

FIG. 5 is a third side view of the soap dispensing scrubber of FIG. 1;

FIG. 6 is a fourth side view of the soap dispensing scrubber of FIG. 1;

FIG. 7 is a top view of the soap dispensing scrubber of FIG. 1; and,

FIG. 8 is a bottom view of the soap dispensing scrubber of FIG. 1.

1 Claim, 8 Drawing Sheets
